UNITED STATES PATENT OFFICE.

HENRY C. BRILL, OF SOUTHBURG, CONNECTICUT, ASSIGNOR TO THE SOUTHBURG CUTLERY COMPANY, OF SAME PLACE.

DESIGN FOR A CURRY-COMB.

SPECIFICATION forming part of Design No. 13,457, dated November 28, 1882.

Application filed May 6, 1882. Term of patent 14 years.

To all whom it may concern:

Be it known that I, HENRY C. BRILL, a citizen of the United States, residing at Southbury, in the county of Hartford and State of Connecticut, have invented and produced a new and original Design for Curry-Combs, of which the following is a specification, reference being had to the accompanying drawing, forming part thereof.

- 10 Said drawing is a perspective view, which fully illustrates my design.
- A designates the body of the comb-frame, B the handle, C the connecting brace or bracket, and D the middle bar of said frame. The ordinary comb-bars extend transversely to the length of the comb-frame upon the under side thereof. By the body of the comb-frame I mean that part of the comb to which the toothed comb-bars are secured as a distinct and separate part from the toothed comb-bars themselves. I make this body in the form and configuration of a horseshoe, and I connect it to the shank of the handle by means of the brace or bracket C, which extends upward from the upper inside corners of the heel portions of the frame. The middle portion or bar, D, which also forms a portion of the comb-frame, is in the form of the frog of a horse's foot at the handle end, while the opposite end of said bar 20 is straight. At the end of the frame, which represents the toe of the horseshoe, there is a slight enlargement to make room for the eye or opening a; but this feature may be omitted, if desired. The making of the body A of the frame 30 rounded in horseshoe form necessitates making the comb-bars of varying lengths, as shown. This body A is not only rounded, so that its outer edge is in the form of a horse's shoe, but it is flattened or made of greater dimensions 35 from its outer to its inner edge than it is from its back to its front or under side, while the back or upper side has creases with block-

shaped projections therein in the form of the creases and nail-heads on the under side of a horse's shoe.

I am aware that a prior patent shows a curry-comb in which the frame is composed of a shank having four curved arms extending laterally from the shank, and a single comb bar or plate made in semi-oval or horseshoe shape and secured to the ends of said arms, and the same is hereby disclaimed. My design is readily distinguished therefrom by having the frame in a semi-oval form, and having the ordinary comb-bars extend transversely to said frame, thereby imparting to the complete design such a radically-different appearance that there is no probability that one could possibly be mistaken for the other.

I claim—

1. The design for a curry-comb herein shown and described, the same consisting of the rounded and flattened body A of the frame, and upon the under side thereof comb-bars of varying lengths, whose ends substantially correspond to the rounded side edges of the frame.

2. The design for a curry-comb herein shown and described, the same consisting of the rounded and flattened body A of the frame, in horseshoe form, and the curved brace C, extending upward from the upper inside corners of the heel portion of the frame.

3. The design for a curry-comb herein shown and described, the same consisting of the body A of the comb-frame in the form and configuration of a horseshoe, the middle bar, D, of said frame having the end which is between the heel portions of the body A in the form of the frog of a horse's foot, and the comb-bars extending transversely to the comb-frame.

HENRY C. BRILL.
